UNITED STATES PATENT OFFICE.

WILLIAM W. BURESCH, OF BALTIMORE, MARYLAND.

BOTTLE-CAPPING TOOL.

1,276,323.

Specification of Letters Patent. Patented Aug. 20, 1918.

Application filed August 28, 1917. Serial No. 188,550.

To all whom it may concern:

Be it known that I, WILLIAM W. BURESCH, a citizen of the United States, residing at Baltimore, in the State of Maryland, 5 have invented certain new and useful Improvements in Bottle-Capping Tools, of which the following is a specification.

This invention relates to bottle capping devices, and more particularly to hand tools 10 for applying crimped caps to bottles.

The object of the invention is to provide a convenient, efficient and practical hand tool for replacing crimped caps on bottles so as to restore the bottles to the same 15 tightly closed condition in which they were before the caps were removed. Incidentally, my improved bottle capping tool can be so shaped as to serve also as a cap remover or bottle opener.

20 In order that the invention may be readily understood, reference is had to the accompanying drawings, forming a part of this specification, and in which,

Figure 1 is a face view of one form of my 25 improved cap removing and replacing tool;

Fig. 2 is an edge view thereof;

Fig. 3 is a central, longitudinal section; and,

Fig. 4 is a view similar to Fig. 1, but 30 showing a modified construction.

Referring to Figs. 1 to 3, the improved tool therein illustrated comprises a pair of handle members 1—2, pivoted together at one end, as indicated at 3. These handles 35 are preferably of the curved form shown so that they may be readily grasped in the palm of the hand, after the manner of pliers.

Secured to the inside of the handle members 1 and 2, and disposed between the same, is a pair of flat, semi-annular die members 4 and 5. These die members lie in the same plane and are so proportioned that their ends abut when the handles are pressed together.

The die members 4 and 5 are provided around their inner edges with a series of points or teeth 6. The number and shape of these teeth correspond approximately with 50 the indentations or corrugations of the bottle cap to be operated upon. Such a cap is indicated at X in dotted lines, and is shown in Fig. 3 as fitted to the mouth of a bottle, designated at Y.

The under face of the die members adjacent the teeth 6 is preferably beveled, as indicated at 7, so as to conform to the shape of the flaring lower edge of the cap.

The outer edge of the die members 4 and 5, on the side adjacent the pivot 3, is preferably cut away and beveled off to form an edge 8, adapted to engage under a bottle cap and serving, in combination with those portions of the handle members 1 and 2, adjacent the pivot, as a cap remover or bottle 65 opener, as will be obvious.

In operation, the cap is laid in place on the bottle and the tool positioned around and over the cap, as illustrated in Fig. 3, with the teeth 6 fitting into the notches or 70 corrugations of the cap. The tool is then grasped in the hand and the levers pressed firmly together while the bottle is struck a slight blow upon a table or the like, thus forcing the cap down over the bead of the 75 bottle neck and crimping it in position.

In Fig. 4, I have shown a modified form of tool adapted for operation with both hands. In this case, the tool comprises a pair of levers crossed and pivoted together 80 at 13 and forming two pairs of handles 9—10 and 11—12. Die members 14—15, similar to the die members 4 and 5, are secured to the levers, the point of attachment shown being between the handles 11—12 85 and the pivot 13. The die members 14—15 are provided with interior teeth 16, similar to the teeth 6.

In using the device shown in Fig. 4, a pair of handles is grasped by each hand 90 and the cap pressed down over the bottle mouth and crimped by squeezing.

By the use of my improved tool, it will be seen that bottle caps may be easily and quickly replaced and that in this way, the 95 same caps may be used repeatedly. This also makes it possible to use only part of the contents of a bottle and preserve the remainder indefinitely, as desired.

What I claim is:

1. A bottle capping tool comprising a pair of handle members pivoted together, and a coöperating pair of flat, semi-annular die members secured to said handle members, said die members being provided at 105 their inner edges with a series of teeth adapted to engage the corrugations of a bottle cap, one face of the die members adja-

100

105

cent the teeth being beveled so as to conform to the flaring edge of such cap.

2. A tool of the character described comprising a pair of handle members pivoted together at one end, and a coöperating pair of flat, semi-annular die members secured to said handle members and located between

the same, said die members being provided at their inner edges with a series of teeth adapted to engage the corrugations of a bottle cap. 10

In testimony whereof I have affixed my signature.

WILLIAM W. BURESCH.

Copies of this patent may be obtained for five cents each, by addressing the "Commissioner of Patents, Washington, D. C."
